UNITED STATES PATENT OFFICE.

JAMES L. CAMPBELL, OF WEST ELIZABETH, PENNSYLVANIA.

DESIGN FOR A GRATE.

SPECIFICATION forming part of Design No. 32,539, dated April 17, 1900.

Application filed March 17, 1900. Serial No. 9,115. Term of patent 14 years.

To all whom it may concern:

Be it known that I, JAMES L. CAMPBELL, a citizen of the United States, residing at West Elizabeth, in the county of Allegheny and State of Pennsylvania, have invented and produced a new and useful Design for Grates, of which the following is a specification.

Figure 1 is a front or face view of a grate, showing my new design. Fig. 2 is a vertical section of the same on the line 2 2, Fig. 1. Fig. 3 is a transverse section on the line 3 3, Fig. 1.

As shown in said drawings, the leading and essential feature of my new design is a grate having a curved top 1, with a swell or rounded margin 2 surrounding the top and sides, flaring inside walls 3, a slightly-inclined top 4, a reversely-inclined bottom 5, and an inclined back 6.

An offset 7 is formed on the lower portion 20 of the back 6, and the front face of this offset inclines backwardly toward the bottom. The base-flange 8 is substantially plain and flat, and projecting upwardly from the bottom 5 is an oval perforated burner 9. 25

What I claim, and desire to secure by Letters Patent, is—

The design for a grate substantially as shown and described.

In testimony whereof I have hereunto set 30 my hand in presence of two subscribing witnesses.

JAMES L. CAMPBELL.

Witnesses:

LAURENCE CAMPBELL,
J. C. DONALDSEN.
